UNITED STATES PATENT OFFICE

PAUL E. HILL AND IRA C. MATTHIESSEN, OF CHICAGO, ILLINOIS, ASSIGNEES, BY MESNE ASSIGNMENTS, TO AMERICAN AUTOMATIC TYPEWRITER CO., OF CHICAGO, ILLINOIS, A CORPORATION OF ILLINOIS

RECORD PERFORATING MACHINE

Application filed February 23, 1929. Serial No. 342,023.

This invention relates to record perforating machines, and the principal object is to provide electrically operated means for rotating the winding roll, upon which the record is wound, in a step by step manner while being perforated. Machines of this type are used for preparing records, such as are employed in pneumatically operated mechanism for typewriters and other instruments, for reproducing the subject matter represented by the perforations in the record. Another object is to provide electrically operated roll advancing mechanism under the control of the key levers of the machine.

Another object is to provide a record perforating machine having electrically operated means for actuating the winding roll wherein the current is momentarily passed through the electric or magnetic device whenever a key lever is released after having been depressed, whereby the record is advanced one step after each perforation has been made. Another object is to provide novel electrically operated record advancing means which shall be extremely rapid, whereby the key levers may be actuated in rapid succession without any danger of injury to the record.

Further objects and advantages will appear in the course of this specification, and with such objects and advantages in view, this invention consists in a record perforating machine embodying electrically operated means under the control of the key levers for rotating the winding roll in a step by step manner. The invention further consists in a record perforating machine having electrically operated means for rotating the winding roll and provided with circuit closing means actuated by the key levers in such timed relation that the record is advanced while the perforating dies or plungers are disengaged from the record.

The invention further consists in the several novel features of construction, arrangement and combination of parts hereinafter fully set forth and claimed.

The invention is clearly illustrated in the drawings accompanying this specification in which—

Figure 1 is a plan, partly broken away, of a record perforating machine embodying a simple form of the present invention;

Fig. 2 is a vertical longitudinal section taken on the line 2—2 Fig. 1; and

Fig. 3 is a plan of a certain contact making and breaking lever for the electrically operated record advancing means.

Referring to said drawings, which illustrate a simple embodiment of the present invention, the reference character 5 designates the supporting frame of the machine which, as here shown, comprises two side frame members 6 and 6^a connected by transverse rods or bars 7. The frame is provided with suitable legs 8 upon which the machine stands.

Removably and rotatably mounted between the side frame members adjacent one end thereof is a roll 9 upon which the unperforated record, designated by the character 10, is wound, and at the other end of the machine is a winding roll 11, which is also rotatably mounted between the side frame members, and may be removably mounted thereon, if desired. In the operation of the machine, the record 10 is unwound from the roll 9 and wound upon the roll 11 in a step by step manner as will be hereinafter explained.

Pivotedly mounted upon a transversely extending rod 12 are key levers 13 and the arms 14^a of a space bar 14. Adjacent the rod 12 is a transversely extending vertically slotted bar 12^a, and adjacent the forward ends of the key levers is a slotted bar 15, both of which are supported by the side frame members. The key levers extend through and are guided in the vertical slots and are spaced apart thereby. Each key lever and the arms of the space bar are yieldingly held against the upper ends of the slots in the bar 15 by coiled tension springs 16 secured to said key levers and arms of the space bar and to a cross bar 17 which extends between the side frame members and is secured thereto.

The keys of the key levers bear characters and other indicia, and when the machine is employed for perforating records for use on pneumatically operated mechanism for typewriters, the keys correspond to the letters of the alphabet, the digits, and other indicia

required in connection with the work of perforating the record.

Between the spindle 9 and record roll 11 is a stationary female die 18 containing apertures 22 disposed in vertical alignment with the key levers, and above said die is a guide bar 19 to which said die 18 is secured; as, for instance, by screws 20. A narrow space or slit is left between the guide bar 19 and die 18 through which space the record may pass. Connected to each key lever 13 and to the arm of the space bar 14 is a punch or male die 21 which extends down through a hole in the guide bar 19 and is adapted to enter one of the apertures 22 in the die 18. The punch may be in the form of a round rod which cooperates with the round apertures 22 in the die in punching out the perforations in the record. The dies are disposed crosswise of the record and are spaced apart so as to correspond with the locations of the slots in the tracker bar of the pneumatic instrument in which the record is used. The record 10 passes under and over tension bars 10^a and 10^b interposed between the roll 9 and the die 18. Said tension rods are supported by the end frame members of the machine.

The connection between the key levers and punch may assume any desired form, and, as shown in the drawings, the upper end of each punch 21 is made in the form of a spherical head 23 connected to the body portion of the punch by a neck, the head being confined in a socket in the key lever conforming generally to the shape of the head and neck, as is clearly illustrated in Fig. 2. It will be understood that the perforations in the record are made by depressing the key levers and space bar. After each perforation has been made, the record must be advanced one step, and the mechanism for so advancing the record will now be described.

Upon one end of the winding roll 11 is a ratchet wheel 24, and below said ratchet wheel is a lever 25 pivoted at one end to the side frame member 6 and having secured to it a pawl 26 which is arranged to engage with the teeth of the ratchet wheel 24. A spring 27 connected to the pawl and to the lever 25 serves to yieldingly hold the pawl in engagement with the ratchet wheel. A spring actuated detent 28 pivotally mounted upon the side frame member 6 engages with the ratchet wheel 24 and prevents retrograde movement thereof.

A solenoid or other electromagnetic device 29 is supported by the end frame member 6 above the free end of the lever 25, and the core 30 of the solenoid is connected to the lever by a pin 31. A coiled compression spring 32 confined between the solenoid 29 and lever 25 serves to depress the end of the lever connected to the core, and a lug or other stop member 33 is provided on the frame member 6 to limit the downward movement

of the lever. It will be observed that whenever the solenoid is energized, the core 30 is drawn upward and the lever 29 is thereby swung upward carrying the pawl 26 with it and rotating the ratchet wheel and therewith the winding roll 11 and advancing the record 10 one step.

Means controlled by the key levers and space bar and by the solenoid are provided for making and breaking the circuit through the solenoid whenever a key lever or the space bar is released after having been depressed to form a perforation in the record. The electric control means will now be described.

Below the key levers and arms of the space bar is a transversely extending bar 34 which is arranged to be depressed by each lever and the arms of the space bar whenever those members are depressed, and said bar 34 actuates the contact making and breaking members. Pivotedly mounted on the side frame member 6 is a contact lever 35, one end of which is connected to the bar 34 by a link or rod 36 having a lost motion connection with the contact lever 35. A contact member 37, carried by one end of the lever 35, is arranged to be brought into contact with a stationary contact member 38 carried by a bracket 39 and secured to the side frame member 6.

A spring actuated detent 40 secured to the side frame member 6 engages with the lever 35 and serves to hold the same in the two positions occupied by it, namely, the position wherein the contact pieces 37 and 38 make contact with each other and the one wherein they are separated. As shown, one end of the lever 35 is formed with a pointed or tapered end 41 against which the detent 40 bears, the arrangement being such that the peak at the pointed end of the lever passes the engaging part of the detent when moved from one to the other of its operative positions. The detent acts by reason of its pressing engagement with the inclined edges of the end portion of the lever to hold it in either of its said two positions.

On the contact lever 35 is a lug or other shoulder 35^a which is arranged to be struck by the lever 25 whenever the latter is moved upwardly by the solenoid. When the shouldered end of the contact lever 35 is moved upwardly, the contact piece 37 is moved down, thereby breaking the circuit for the solenoid through the contact pieces 37 and 38. The shoulder 35^a may have an adjustment screw threaded therein for affording adjustment between the levers 25 and 35.

The contact piece 37 is electrically connected to the solenoid 29 by an electric conductor 42 which may be fastened to a binding post 43 carried by the lever 35, and the stationary contact piece 38 is electrically connected to a second stationary contact

piece 44 by an electric conductor 45, the ends of which are secured to the bracket 39 and to the bracket 46 in which the stationary contact piece 44 is mounted. A second movable contact piece 47 co-operates with the stationary contact piece 44 in closing the circuit through the contact pieces 37 and 38 and the solenoid, and said movable contact piece 47 is actuated by the bar 34.

10 As shown, the bar 34 comprises part of a rectangular rocking frame 48 pivotally mounted upon the side frame members 6 and 6^a. The frame 48 may comprise the bar 34, a bar 49, parallel therewith, and end bars 15 50. Pins or stud shafts 51 mounted in the side frame members afford the pivotal connection between the frame 48 and said side frame members. The movable contact piece 47 is secured on one end of the end bar 50 in 20 position to contact with the stationary contact piece 44. A spring 52 connecting the rocking frame 48 with the side frame member 6 serves to hold the bar 34 of said locking frame in raised position underneath the 25 key levers and also serves to hold the movable contact piece 47 in contact with the stationary contact piece 44, except when a key lever or space bar is depressed. In normal position of the bar 34, the contact piece 37 is held out 30 of contact with the contact piece 38, whereby the circuit through the solenoid remains broken so long as all of the key levers remain in their normal position.

An electric conductor 53 leads from a binding post on the end bar 50 and an electric conductor 54 leads from the solenoid, and said electric conductors 53 and 54 may lead to any suitable source of electric supply. It will be understood that the contact lever 35 and 40 rocking frame 38 are insulated from each other and from the brackets 39 and 46 and that the circuit through the solenoid is closed only when both movable contact pieces 38 and 47 are in contact with the stationary contact 45 pieces 37 and 44. A lever 55 fulcrumed on the side frame member 6 is provided for manually actuating the pawl 26 in case it is desired to advance the record independently of the roll advancing mechanism.

50 In the operation of the machine, the end of the unperforated record carried by the roll 9 is passed between the tension rods 10^a and 10^b and through the slit between the die 18 and bar 19 and is secured to the winding roll 11. The record is perforated by depressing the key levers and space bar in the ordinary manner of operating a typewriter. Each time a key lever or the space bar is depressed, the punch or male die 21 punches a perforation 55 in the record.

When a key lever is depressed, the bar 34 of the rocking frame 48 is swung downward and therewith one end of the contact lever 35 is depressed, while the end containing the 65 movable contact piece 37 is swung upwardly,

thereby bringing said movable contact piece into contact with the stationary contact piece 38. The detent 40, by reason of its engagement with the lever 35, holds said lever in the position so occupied by it with the contact pieces 37 and 38 in contact, although the bar 34 and link 35 are moved upward when the key lever is released.

The downward movement of the bar 34, caused by the downward movement of the key lever, results in an upward movement of the part of the rocking frame 48 which carries the movable contact member 47, and, consequently, the contact pieces 44 and 47 are held out of contact so long as the bar 34 remains depressed. It will be seen, therefore, that whenever any key lever is depressed, the circuit to the solenoid is closed through the contact pieces 37 and 38, but is broken between the contact pieces 44 and 47. As soon as the depressed key lever or space bar is released, the spring 16 returns the key lever to normal position and the spring 52 returns the frame 48 to the normal position, thereby bringing the movable contact piece 47 into contact with the stationary contact piece 44 and closing the circuit through the contact pieces 37 and 38 and through the solenoid, which being energized, draws up the long arm of the lever 25 and advances or rotates the ratchet wheel 24 one step through the engagement of the pawl 26 therewith. Consequently, the record is advanced one step upon the roll 11.

As the lever 25 moves upwardly it encounters the shoulder 35^a on the contact lever 35, thereby swinging upwardly the end of the lever 35 which is connected to the link 36, and swinging down its other end, consequently separating the contact pieces 37 and 38 and breaking the circuit through the solenoid. It will be seen, therefore, that the closing of the circuit through the solenoid is timed to take place whenever a key lever is released after having been depressed, and that the circuit is broken the instant that the roll 11 has been advanced one step.

The two circuit closing members for the electric circuit of the solenoid operate in reverse order, so that normally the circuit is open at one of said places and remains open at one or the other of said places at the raised or depressed position of any of the key levers, except at the instant a key lever returns to its raised position after having been depressed. The action of said circuit closing members in breaking the circuit at one place and closing it at another and vice versa may be regarded as reversely acting in the following claims.

We claim:

1. In a record perforating machine, the combination with key levers, record perforating dies actuated thereby and a winding roll for the record, of electrically operated roll advancing mechanism including an electro-

magnetic device, and two key lever operated switches contained in a normally open series circuit.

2. In a record perforating machine, the combination with key levers, record perforating dies actuated thereby and a winding roll for the record, of electrically operated roll advancing mechanism including an electromagnetic device and two switches contained in a series circuit normally open at one of said switches and closed at the other, and operative connections between said key levers and both switches for closing the open switch and opening the closed switch when a key lever is depressed.

3. In a record perforating machine, the combination with key levers, record perforating dies actuated thereby and a winding roll for the record, of electrically operated roll advancing mechanism, key controlled circuit closing means therefor, and circuit breaking means actuated by said roll advancing mechanism.

4. In a record perforating machine, the combination with key levers, record perforating dies actuated thereby and a winding roll for the record, of electrically operated roll advancing mechanism, key operated mechanism for closing the circuit therefor at two places, and circuit breaking means actuated by said roll advancing mechanism for breaking the circuit at one of said places.

5. In a record perforating machine, the combination with key levers, record perforating dies actuated thereby and a winding roll for the record, of a solenoid, roll advancing mechanism actuated by said solenoid, key controlled circuit closing means for said solenoid, and circuit breaking means actuated by said solenoid.

6. In a record perforating machine, the combination with key levers, record perforating dies actuated thereby and a winding roll upon which the record is wound, of a rocking member having a depressible bar extending transversely underneath said key levers and arranged to be depressed thereby, electrically operated roll advancing mechanism, a circuit closing member actuated by said rocking member when moved in one direction, and a circuit closing member actuated by said rocking member when moved in the opposite direction, both of said circuit closing members being contained in the circuit for the electric element of the roll advancing mechanism, and means actuated by said roll advancing mechanism for breaking the circuit.

7. In a record perforating machine, the combination with key levers, record perforating dies actuated thereby and a winding roll upon which the record is wound, of electrically operated pawl and ratchet mechanism for said winding roll, key controlled circuit closing means, and circuit breaking

means actuated by said electrically operated mechanism.

8. In a record perforating machine, the combination with key levers, record perforating dies actuated thereby and a winding roll upon which the record is wound, of a rocking member having a depressible bar extending transversely underneath said key levers and arranged to be depressed thereby, a solenoid, roll advancing mechanism actuated by said solenoid, two circuit closing members arranged in series and actuated by said rocking member, and circuit breaking means for one of said circuit closing members actuated by said roll advancing mechanism.

9. In a record perforating machine, the combination with key levers, record perforating dies actuated thereby and a winding roll upon which the record is wound, of a rocking member having a depressible bar extending transversely underneath said key levers and arranged to be depressed thereby, an electrically operated element, two circuit closing members arranged in series in the circuit of said electrically operated element and actuated by said rocking member, pawl and ratchet mechanism for said winding roll and actuated by said electrically operated element, and circuit breaking means for one of said circuit closing members actuated by said electrically operated element.

10. In a record perforating machine, the combination with key levers, record perforating dies actuated thereby and a winding roll for the record, of electrically operated roll advancing mechanism, and key operated circuit closing means acting to close the circuit therefor at one place when a key is depressed, and to complete the circuit at another place when the key is released.

11. In a record perforating machine, the combination with key levers, record perforating dies actuated thereby and a winding roll for the record, of electrically operated roll advancing mechanism, key operated circuit closing means acting to close the circuit therefor at one place when a key is depressed and to complete the circuit at another place when the key is released, and actuating means operated by said roll advancing mechanism for breaking the circuit at the first mentioned place.

12. In a record perforating machine, record perforating dies, key levers therefor, a key lever controlled electrically operated winding roll advancing mechanism having two reversely acting circuit closing members arranged in series.

13. In a record perforating machine, record perforating dies, key levers therefor, a circuit closing lever, operative mechanical connections between the key levers and the circuit closing lever for moving the latter to active position, means for holding said circuit closing lever in active and inactive

positions, and automatically operating mechanism for moving said circuit closing lever into inactive position.

14. In a record perforating machine, the combination of a circuit closing lever, key lever operated means connected to said circuit closing lever for setting the same into active position for closing the circuit, a winding roll, and an electrically operated roll advancing mechanism having a member adapted to engage and set said circuit closing lever into inactive position.

15. In a record perforating machine, record perforating dies, key levers therefor, a key lever operated circuit closing lever, connecting means between the key levers and said circuit closing lever for moving said circuit closing lever into active position, automatically operating mechanism for moving said circuit closing lever into inactive position, and spring actuated means for holding said circuit closing lever in both of said positions.

16. In a record perforating machine, record perforating dies, key levers therefor, a key lever operated circuit closing lever, means for holding said circuit closing lever in active and inactive positions, a record winding roll, pawl and ratchet mechanism for said roll, a lever to which the pawl is connected, and a solenoid for operating said last mentioned lever, said solenoid being contained in a normally open circuit, the latter lever being arranged to set said circuit closing lever into inactive position.

17. In a record perforating machine, the combination with key levers, record perforating dies actuated thereby, and a winding roll for the record, of a rocking frame having a depressible bar underneath the key levers, an electro-magnetic element, a circuit closing member therefor having a lost motion connection with the rocking frame, and a second circuit closing member in series with said first mentioned circuit closing member and actuated by said rocking frame, and roll advancing mechanism actuated by said electro-magnetic element and having a member arranged to actuate said first mentioned circuit closing member to thereby break the circuit through said member.

18. In a record perforating machine, the combination with key levers, record perforating dies actuated thereby and a winding roll for the record, of a depressible bar underneath the key levers, a contact lever having a lost motion connection with said bar, an electro-magnetic element, movable contact pieces, one carried by said contact lever and one actuated by said depressible bar, companion stationary contact pieces, said contact pieces being arranged in series in the circuit to said electro-magnetic element, and roll advancing mechanism operated by said electro-magnetic element, and arranged to actuate said contact lever in a direction to

break contact through the contact member carried thereby.

In testimony whereof, we have hereunto set out hands this 23rd day of November, 1928.

PAUL E. HILL.
IRA C. MATTHIESSEN.
